UNITED STATES PATENT OFFICE.

CHARLES J. HEILEMAN, OF PARK HILLS, KENTUCKY.

WRIST-WATCH BAND OR STRAP MOUNTING.

Application filed May 9, 1927. Serial No. 190,024.

This invention relates to wrist-watch mountings, or, more particularly speaking, to the coupling-connections between the usual spaced lateral lugs of the watch-holding frame or case and the wrist band or strap, for attachment in using place.

The direct object of the invention is to provide a coupling-sleeve connection that extends laterally beyond the attaching ends 10 of the said wrist band or strap and makes due allowance for a number of different widths and thicknesses of said bands to suit the size of the watch-holding frame or case and the arm of the wearer, and with due regard to symmetry or harmony in the use of 15 the wrist-watch product.

The details of structure of the improvement will be fully hereinafter described in connection with the accompanying sheet of 20 drawings, in which latter—

Figure 1 is a plan view of the wrist-watch and its attaching band or strap, showing my improved mounting-connection with a medium width of strap; Fig. 2, a side elevation 25 of the complete structure; Fig. 3, a fragmentary plan, partly in section, showing the improved mounting-connection herein; Fig. 4, a detail section of the mounting-connection, taken on the dotted line 4, 4, of Figs. 2 and 30 3; Fig. 5, a perspective of one of the sleeves forming a part of the said mounting-connection, such sleeve in this view having a narrow slot for a thin band or strap; Fig. 6, a 35 plan of the strip of sheet metal used in forming the sleeve seen in Fig. 5; Fig. 7, a perspective similar to Fig. 5, but showing the sleeve with a wide slot for a heavier or thicker band or strap; and Fig. 8, a plan of the strip of sheet-metal used in forming the sleeve 40 seen in Fig. 7.

In these views of the drawings, A indicates the usual watch-holding frame adapted to contain the encased dialed movement or watch-proper B and having spaced lugs C, C, 45 at its opposite ends for the hinged or pliable reception of the opposite ends of the wrist band or strap D.

The wrist-band, in use, is made in different widths and of different thicknesses of material, and it is desirable that the hinged connection or coupling member between the said opposite ends of it be constituted so as to properly conform to or well meet its said varying thicknesses and widths. To such end my invention herein is essentially and peculiarly 50 adapted. The coupling-connection herein, 55

therefore, is composed of a short length of tubing 9 that forms a sleeve to fit freely, but not loosely, between each of the pairs of extended lugs C, C, at the opposite ends of the watch-holding frame A. Each of the sleeves 9 is formed from a flat rectangular strip of sheet-metal or blank, as shown at a and b, in Figs. 6 and 8, respectively, the strip a, in Fig. 6, having at one end thereof an elongated notch or cut-out shouldered portion a', and the strip b, in Fig. 8, having at both ends thereof similar notches b'. In forming the tubing from these strips the strip a, of Fig. 6, is used to produce the sleeve of Fig. 5, to 60 accommodate the eye or loop 10 at each end of the wrist-band D that is slipped into place within the sleeve, (which latter is of spring or resilient metal), by opening the slit between the opposite adjacent ends of the elastically-closed strip a. When the said eye has 65 reached the position of the notch a', so as to fully register therewith, it becomes automatically seated or snaps into its proper place in the sleeve, the shouldered ends of the notch 70 preventing its endwise movement or displacement from the sleeve until required to do so and accomplished by spreading open the said spring-closed meeting ends of the tubing-strip a. In order to meet the varying widths 75 of wrist-bands the sleeves 9 are all made to fit 80 freely, as above stated, between the pairs of lugs C, C, on the watch-holding frame, but the length of notches a is made to vary, a longer notch to suit the wide band and 85 the shorter notch to suit the narrow band, all to suit the varied conditions connected 90 with the individual taste and the size of the arm or wrist of the wearer. In actual 95 practice, however, it has been found necessary to allow for but about three widths of bands, viz: a broad, a medium, and a narrow band, and sleeves with corresponding lengths 100 of notches a, to suit the width of band, are selected for the demands of the trade. To further provide for thicker bands I notch the strip b at its opposite ends, as above stated, and, when the said opposite ends are brought together under the tension of the spring metal thereof, the notches b' duly register 105 to form a broader slot or opening for the accommodation of the thicker or heavier metal of the eye or loop 10 at the opposite ends of the said band. The adjustment or change from a broad to a narrow band, or 110 the reverse, can be readily made by the substitution of sleeves having long, medium, or

short notches to suit such different widths of bands.

A tubular connecting axle or pintle 11, having reduced, internally-headed bearing-ends 12, 12, is provided within each of the said sleeves 9 and, coincidentally, within the end-loops 10, 10, of the band, to flexibly connect the latter with the opposite lugged ends of the watch-holding frame A. The said bearing-ends 12 of the pintle 11 engage minute openings 13 in the lugs C and such pintle, being hollow, is thereby adapted to accommodate the said bearing-ends in a resiliently-extended manner by the additional use of an internal spiral spring 14, as best seen in Fig. 3. A short tubular filler-plug 15 is inserted, with a drive-fit, in each end of said hollow pintle 11 to prevent any undue movement of said bearing-ends. Thus, the said pintle can be conveniently placed between the lugs with its spring-extended bearing-ends in the openings 13 for the free flexible connection of the opposite loop-ends of the wrist-band therein.

The bearing-ends can be easily displaced by simply inserting a pointed instrument in either opening 13 and compressing either of said bearing-ends until it clears the inner face of the adjacent lug. The compression of either of the little spring-extended spindles 12 will permit the main spindle or pintle 11 to be inserted or withdrawn to and from place between the said pairs of lugs C, C, for the attachment or detachment, as the case may be, of the encased time-piece between the opposite ends of the wrist-band. Intermediate the said opposite ends of the wrist-band is

provided a suitable clasp E to connect, in adjusted position on the wrist, the customary pair of arc-shaped members that form the said wrist-band.

40

The opposite ends of the sleeves 9 are preferably, but not essentially, inwardly flared, as best seen in Fig. 3, to cover or inclose the gap over the ends of the eyes or loops 10 and impart the desired workmanlike and aesthetic effect or finish to the device for use.

It is intended that the improved mounting herein is adapted for similar expansible use with a leather belt of various widths and its buckle, instead of a watch-holding frame, substituted for use in a flexibly-connected manner to the belt.

I claim:—

In a wrist watch mounting, a wrist band having at one end thereof a connecting loop formation, a watch holding frame having a pair of lugs, a transverse detachable tubular pintle having extensible bearing ends that journal in aligned holes in the outer ends of said lugs, said loop formation concentrically encompassing said tubular pintle, and a longitudinally-split elastically closed auxiliary coupling sleeve concentrically encompassing the said tubular pintle and loop formation between the lugs and having a longitudinal slot adapted to accommodate the width of the wrist band free from cross-wise shifting of the mounting.

In testimony whereof I hereunto affix my signature.

CHARLES J. HEILEMAN.
